F. C. JENTÖ

ELECTRIC WATER HEATER

Filed April 24, 1923

UNITED STATES PATENT OFFICE.

FORD CHARLES JENTO, OF HAMILTON, ONTARIO, CANADA, ASSIGNOR OF ONE-HALF
TO ARTHUR McINTYRE, OF HAMILTON, ONTARIO, CANADA.

ELECTRIC WATER HEATER.

Application filed April 24, 1923. Serial No. 634,336.

To all whom it may concern:

Be it known that I, FORD CHARLES JENTO, a subject of the King of Great Britain, and a resident of the city of Hamilton, in the county of Wentworth, Province of Ontario, Dominion of Canada, have invented certain new and useful Improvements in Electric Water Heaters, of which the following is a specification.

10 My invention relates to improvements in electric water heaters and the object of the invention is to devise an efficient electric water heater of light and inexpensive construction and which may be made in either 15 a portable or a stationary type.

My invention consists essentially of an electric water heater comprising a water container formed by winding a tube into a spiral and fitting a core carrying an electric 20 heating element axially within the spiral, and a suitable casing for the water container and heating element, all as herein-after more particularly described and illustrated in the accompanying drawings in 25 which:—

Fig. 1 is a sectional elevation taken on the staggered line 1, 1, 1, 1, 1 of Fig. 2.

Fig. 2 is a cross section taken on the line 2, 2 of Fig. 1.

30 In the drawings like characters of reference indicate corresponding parts in the different views.

1 is an open ended cylindrical tubular casing having the end caps 2 and 3.

35 4 are closure plugs having threaded engagement at 5 within threaded orifices 6 in the cap 3.

These plugs are provided with axial passageways 7 therethrough. The purpose of 40 these plugs will presently appear.

8 is any suitable heat insulating material which is contained within the casing 1. This material completely fills the casing with the exception of a portion 9 at the 45 end adjacent to the cap 3 for a purpose as will herein-after appear.

The material 8 is provided with cylindrical recesses 10 which extend longitudinally thereof from the end face 11 into proximity 50 to the cap 2.

12 are water containers which are formed by spirally winding a copper tube.

The diameter of these spirals is such that they closely fit within the recesses 10.

55 13 are water inlet connections which pass

through orifices 14 in the cap 2 and communicate with the adjacent ends of the spirals 12.

15 is the main water inlet and 16 is an inlet valve.

The main inlet 15 is connected by suitable T-connections so that all the inlets 13 are fed therefrom.

The opposite ends of the spirals 10 communicate with outlet connections 17 which 60 connections lie within the unfilled space 9 at the end of the container and extend outwardly through an orifice 18 in the side of the casing 1.

Outside the casing the outlet connections 70 17 are suitably connected to a header 19 from which a single discharge pipe 20 leads.

21 are cores of porcelain, soapstone or other suitable material which carry electrical heating elements 22, but as these cores 75 and heating elements are of standard construction forming no part of my invention detailed description is not thought necessary.

The diameter of the cores 21 is such that 80 they closely fit within the spirals 12 and extend axially therethrough.

23 are the electric wiring terminal connections leading from the heating elements 22 and these terminals 23 extend through 85 the orifices 7 in the plugs 5 and are suitably connected to the supplying electric circuit 24.

25 is an electric switch.

The construction and operation of my invention is as follows:

The spiral water containers 12 are mounted in position within the casing and the inlet and outlet connections suitably formed.

In the type illustrated brazed copper tubing is used but of course any suitable type of pipe fittings may be employed.

After the spirals 12 are mounted, the end cap 3 is attached.

The cores 21, with the heating elements 100 22 carried thereby, are then inserted as a unit through the orifices 6 in the cap 3 and extend completely through the spiral water containers, their inner ends resting against the end faces of the recesses 10.

The closure plugs 4 are then mounted and their inner ends engage the outer ends of the cores 21 and thus hold the cores securely in position and prevent any axial movement thereof.

The leads 23 from the heating elements pass out through the small orifices 7 in the plugs 4 and are connected to the electric circuit 24.

Upon opening the inlet valve 16 water may be fed, at any desired rate, through the spiral containers 12 and the discharge from all these spirals is fed out through the common discharge 20.

By making the cores 21 a close fit within the spirals 12 the heating efficiency is increased and further by enclosing the spirals in the heat insulating material 8 the loss by radiation is practically eliminated.

The cores 21 may be quickly and conveniently withdrawn through the orifices 6 without having to remove any part of the device except the closure plugs 4.

Many modifications may be made without departing from the spirit of the invention or the scope of the claim and therefore the exact form shown is to be taken as illustrative only and not in a limiting sense.

For instance, while I have shown a heater having four spirals and heating elements, obviously this number might be altered as desired and one or any desired number might be used.

Also if desired further heating elements might be provided surrounding the spirals.

What I claim as my invention is:

An electric water heater comprising an enclosed casing containing heat insulating material formed with a plurality of longitudinally extending cylindrical cavities having smooth walls, a spiral water container within each cavity, an inlet connection common to all containers and all containers connected to a common outlet connection, a cylindrical core having a smooth peripheral surface extending axially through each spiral and being of size and shape to closely fit within the spiral, a heating element carried by each core, a plurality of removable closures carried by the casing at one end thereof axially opposite each spiral respectively and permitting when removed the withdrawal of the cores and heating elements, said closures constituting when inserted means for securing the cores against axial movement.

FORD CHARLES JENTO.
